UNITED STATES PATENT OFFICE.

ALEXANDER PRINGLE AND THOMAS SINCLAIR KIRK, OF BELFAST, IRELAND.

ARTIFICIAL LIMB.

1,397,654.

Specification of Letters Patent. Patented Nov. 22, 1921.

Application filed August 6, 1920. Serial No. 401,606.

To all whom it may concern:

Be it known that we, ALEXANDER PRINGLE, of 12 Springdale Gardens, Belfast, Ireland, and THOMAS SINCLAIR KIRK, of 21 University Square, Belfast, Ireland, both subjects of the King of Great Britain and Ireland, have invented certain new and useful Improvements Relating to Artificial Limbs, of which the following is a specification.

10 This invention relates to joints for artificial limbs, its object being to provide improvements therein.

According to the invention the joint, which is particularly adapted for use as an 15 elbow but may be used for other purposes, consists of a combination of oppositely disposed toggles which are, or are adapted to be, connected with the limb. Locking means may be provided in connection with the toggles whereby the joint may be locked or 20 secured in different positions.

The invention will now be described with 25 reference to the accompanying drawings whereon it is shown applied to an artificial arm.

Figures 1 and 1^a are side elevations of an elbow joint, in accordance with the invention, in different positions and drawn to different scales.

30 Fig. 2 is an elevation looking in the direction of the arrow α Fig. 1.

Fig. 3 is an elevation of an artificial arm having the elbow joint illustrated by Figs. 1 and 2 applied thereto.

35 Fig. 4 shows an arm with a similar construction of elbow joint but having an upper arm so made and connected with the elbow joint and with the shoulder that the locking of the elbow joint also effects a locking of 40 the shoulder joint.

Figs. 5 and 6 are side and end elevations, respectively, of a modification of the elbow joint shown in Figs. 1 and 2.

Referring to the drawings:—

45 The elbow joint shown at Figs. 1 and 2 comprises three cross frames a , b , and c which, in the example shown, are of cruciform shape (see particularly Figs. 2 and 6). The cross frames a and b are connected by 50 pairs of crossed links d and f while the frames b and c are connected by pairs of crossed links g and h , said links constituting pairs of opposed toggles. The connection of the links d , f , g , and h , with the frames a , b , 55 and c is made by means of pivot pins so that each link has freedom of movement about

the connecting pins in its own plane but resists movements at an angle thereto. The arrangement is such that the joint can be moved freely about a pin k and can be 60 turned through almost 180 degrees to the position shown in the small view at Fig. 1^a.

For the purpose of locking the joint in any position to which it may have been moved two of the links, namely d and h , are provided with segmental projections d^1 and h^1 having series of teeth or indents therein and a locking bolt l is mounted in slots in the cross frame b in such manner that it can be caused to engage the teeth of the segments d^1 and h^1 . The bolt l is under the constant pressure of a spring l^1 (Fig. 2) and has a projection l^2 thereon so arranged that when it is placed above a projection or pin m on the frame b (as shown at Fig. 2 of the drawings) the bolt will engage the teeth in the segments and when the projection l^2 is placed below the pin m the bolt will be held out of engagement with said teeth. Temporary disengagement may be effected by pressing 80 the bolt l , against the action of the spring l^1 , until the notch or recess l^3 therein registers with the toothed segments.

Instead of the locking arrangement hereinbefore described, we may use another locking arrangement in which the locking is effected by frictional action. Such an arrangement is shown at Figs. 5 and 6 and comprises a pin i which extends between the links at each side of the joint and has a fiber distance piece i^1 thereon between said links. The pin i extends beyond the links at each side and engages slots b^1 therein, and also engages slots b^2 in the center cross frame b , so that said frame b is maintained 95 in a central position. Between the links and the cross frame b are two fiber stoppers or washers i^2 and i^3 loose on the pin i . A metal washer i^4 on the outer side of the cross frame b has a cam face i^5 and is loose on the pin i but so engages with the cross frame b that it is prevented from turning with the pin i and is adapted to be acted upon by a cam face i^6 secured to or forming part of the pin i . The pin i is provided with a lever grip i^7 and an adjustable nut to compensate 100 for wear between the parts. The arrangement is such that when the pin i is turned in one direction, the cam face i^6 thereon will coact with the cam face i^5 of the washer i^4 105 and produce a wedging or jamming action on the fiber washers i^2 and i^3 in opposite di-

rections and cause same to lock the links, at both sides of the joint, against the fiber distance piece i^1 . When the pin i is turned in the other direction the links will be freed 5 from this locking action and will thus allow free movement of the joint.

The frame a is connected with a metal end n of the socket of the upper arm o , (see Fig. 3) and, as shown at Fig. 1 the frame a and 10 with it the whole of the elbow and lower arm etc., can be turned relatively to the upper arm o . For this purpose slots n^1 are provided in the end fitting n of the upper arm with which pins a^1 on the frame a engage. One of the pins a^1 is fitted with a 15 screw clamp a^2 whereby the frame a can be clamped to the end fitting n when it is desired to prevent any turning movement between the elbow and the upper arm.

20 A curved plate or member p is shown secured to the frame b . This curved plate p holds out the sleeve of any garment worn by the wearer of the artificial arm, when the arm is bent.

25 A modified construction of upper arm is shown at Fig. 4. In this case the links d^2 and f^2 from the frame b are carried up to the shoulder as shown. This construction does not give quite such an extensive turning movement of the elbow but it gives 30 simultaneous locking of the elbow and shoulder joints.

Having now fully described our invention what we claim and desire to secure by Letters Patent is:

1. In an artificial limb, a joint comprising a plurality of cross frames and oppositely disposed toggles pivotally connected thereto.

2. An artificial limb joint comprising a 40 plurality of frames, oppositely disposed toggles pivotally connected therewith and means for locking said frames against relative movement.

3. In an artificial limb, a joint comprising a frame, oppositely disposed toggles connected with said frame and limb and frictional means for locking the frame and toggles against relative movement.

4. An artificial limb joint comprising a 50 plurality of frames, links pivotally connected with said frames, certain of said links being slotted and means adapted to co-act with

said slotted links and one of the frames to lock the frames against relative movement.

5. An artificial limb joint comprising a 55 plurality of frames, one of which is slotted, links, certain of which are slotted, connecting said frames and means adapted to co-act with said slotted links and frame to lock the joint.

6. An artificial limb joint comprising a 60 plurality of frames, one of which is slotted, links, certain of which are slotted, connecting said frames and a bolt mounted in the slots in said links and frames and adapted to lock the joint.

7. An artificial limb joint comprising a 65 plurality of frames of cruciform shape and links pivotally connected therewith.

8. An artificial limb joint comprising 70 three cross frames, crossed links pivotally connected therewith and means for locking said frames against relative movement.

9. An artificial limb joint comprising a 75 plurality of frames, links connecting said frames, a bolt in connection with a frame and certain of said links and cam means for effecting an axial movement of said bolt and the locking of the joint.

10. An artificial limb joint comprising a 80 plurality of frames, links connecting said frames, a bolt in connection with a frame and certain of said links, cam means for effecting an axial movement of said bolt and the locking of the joint and means for adjusting said bolt to compensate for wear.

11. An artificial limb joint comprising a 85 plurality of frames, crossed links pivotally connected with said frames, and a curved member to prevent sagging of the clothes of the wearer when the joint is bent.

12. In an artificial limb, a joint comprising a plurality of frames and oppositely disposed diagonal links connecting same, a second joint and means for simultaneously 95 locking both joints.

In testimony whereof we affix our signatures in presence of two witnesses.

ALEXANDER PRINGLE,
THOMAS SINCLAIR KIRK.
